MOLD FOR CASTING METAL

Application filed February 6, 1931, Serial No. 513,901, and in Germany November 1, 1930.

This invention relates to a method for the production of compound castings or cast blocks and more particularly to those methods in which several chill moulds secured to yoking plates, are filled with molten metals from separate gates or inlets, preferably simultaneously, by the bottom casting method.

In casting by this method it frequently happens that the different kinds of metals, for instances hard and mild steel, rise at different speeds in the two chill mould sides formed by a known division plate or plates in the chill mould, so that the material in one chill mould side reaches the upper edge of the division plate or plates more quickly and by flowing to the other chill mould side, becomes mixed with the material contained in the latter. This results in the production of unusable heads to the blocks, which is avoided by the present invention.

The mixing of the block sides in the head of the block is avoided according to the invention by using one or more plates projecting beyond the upper edge of the normal division plate or plates. These plates projecting beyond the upper edge of the normal division plates, may be auxiliary division plates suspended from the top into the chill mould and reaching to a point below the upper edge of the normal division plates, or at least one of the normal division plates may be made longer than the other one or the other ones.

In place of the shorter normal division plates may also be used plates of the same height provided in the upper part with cuts or perforations.

The accompanying drawing illustrates diagrammatically examples of division plate arrangements and constructions according to the invention.

Figures 1 and 2 show a vertical central section through a chill mould with an auxiliary plate or plates suspended from the top and forming a siphon-like seal.

Figure 3 is a similar section through a third construction.

Figures 4 and 5 are sections of chill

moulds, illustrating the construction of a division plate according to Figure 6 provided with cuts or perforations.

Figure 6 is a vertical section of a chill mould of a fourth construction. 55

Figure 7 is a vertical section of a chill mould according to a fifth construction.

In the drawing, K is the chill mould, and E¹ and E² are the gates or inlets for the corresponding sides H and W. The letters A 60 indicate the normal division plates, the letters B the suspended auxiliary plates.

As will be seen from Figure 1, an auxiliary plate B is suspended from the top into the chill mould and projects between 65 the division plates A, A', reaching to a point below their upper edge. The auxiliary plate may be perforated in the same way as the division plates A, A', but it may also be solid. Assuming that the material rises in the chill mould side W quicker than in the chill mould side H, it will first flow over the division plate A¹ and rise in the central chamber formed by the division plates A and A¹ until it reaches the bottom edge of the suspended 70 plate B. Here it will be cooled by the plate B and the division plate A so that it will be unable at first to pass into the chill mould side H. In the meantime, the material in the chill mould side H will have risen to 80 such an extent that it will be on the same level as in the chill mould side W.

Figure 2 shows a similar construction with a siphon-like seal, as Figure 1. In this case, only one division plate A is used, at both 85 sides of which there are suspended from the top two auxiliary plates B, B¹. Let it be assumed again that the material rises more quickly in the chill mould side W. The material passing between the plate B¹ and the division plate A, and afterwards between the division plate A and the auxiliary plate B, will then be cooled in such a manner as to delay its further rising, and the material of the chill mould side H will be given time 95 to reach the same level as the material at the other side of the chill mould.

In the construction according to Figure 3, the object aimed at is attained by making one of the two division plates, in this case 100

A^1 , longer than the division plate A . If in this case the material of the chill mould side W rises quicker than the material at the chill mould side H , it will be held up by the division plate A^1 and if the latter melts, will flow through the central chamber formed by the plates A and A^1 . If however the material of the chill mould side H rises quicker, it will flow first over the upper edge of the plate A into the central chamber and if the latter is filled by it, will be cooled by the division plate A^1 . Consequently, in this case also, time is gained, in which the material of the chill mould side W can rise further.

The same result will be obtained by using in place of the shorter division plate A according to Figure 3, a plate A^2 of the same height according to Figure 6, which is provided at the upper part with cuts F (Figure 4) or perforations G (Figure 5).

A further construction is shown in Figure 7, in which three division plates A , A^1 , A^2 , are used, the central one A^2 being higher than the others. The plate A^2 may be perforated or solid. These three plates form two central chambers, of which that facing the more quickly rising chill mould side is more quickly filled by the material of the said side, and the process of mixing in the other central chamber is accelerated, whilst at the same time the division plate A^2 prevents the more quickly rising material from overflowing until the material of the other chill mould side has risen.

In place of the intermediate plates could be used of course also wire netting, sheet metal strips, hoop iron, etc.

The suspended parts need not necessarily be of iron, they may be made also of other metals or other materials such as for instance fireclay, asbestos, wood, cardboard or the like.

The suspended parts need not necessarily be left in the block, they may be withdrawn after casting.

I claim:—

1. A compound-ingot mould provided with a plurality of division plates arranged therein in spaced apart parallel vertical planes, said plates having substantially horizontal limiting edges disposed in vertically spaced planes adjacent to but below the top of the mould.

2. A compound-ingot mould provided with at least two substantially vertical, laterally spaced division plates, said plates terminating at their upper ends below the top of the mould and at least one of said division plates being of greater height than another.

3. A compound-ingot mould provided with two co-extensive division plates of less height than the mould cavity and spaced apart in parallel vertical planes therein, and with a third plate extending downwardly from the

top of the mould cavity between said division plates and to a point below the top of the division plates, for the purpose described.

4. A compound-ingot mould provided with a division plate extending from the bottom of the mould cavity to a point below the top of the mould cavity, and with a plate on each side of said division plate and spaced apart therefrom and extending from the top of the mould cavity to a point below the upper edge of the division plate, for the purpose described.

5. A compound-ingot mould comprising a mould body, and a pair of substantially vertical, laterally spaced plates dividing said mould body into separate compartments, said plates having limiting edges disposed in vertically spaced, substantially horizontal planes adjacent to but below the top of the mould body.

6. A compound-ingot mould comprising a mould body, at least one substantially vertical division plate within the mould terminating at its upper end below the top of the mould, and at least one plate extending downwardly from the top of the mould in lateral spaced relationship to said first mentioned plate and terminating at its bottom above the bottom of the mould and below the top of said first mentioned plate.

In testimony whereof I have signed my name to this specification.
